Application June 11, 1945, Serial No. 598,825

19 Claims. (Cl. 113—38)

1

This invention relates to presses, and more particularly to stamping and drawing presses such as are used for the forming of metal sheets in the manufacture of automobile bodies, side rails, and the like.

Reference is made to my copending application Serial No. 458,686, filed September 17, 1942, now Patent No. 2,378,062, issued June 12, 1945, in which is illustrated and described a press which is adapted for stamping or drawing operations in the forming of parts from metal sheets. Said application also makes reference to problems encountered in the use of large mechanically operating presses for forming automobile body parts, or the like, from thin sheets of metal, especially when such parts are of considerable size, such as a so-called "quarter panel," and which therefore require presses of very large size. As stated presses such as are used for forming automobile body parts from such thin metal sheets have been 30 or 40 feet or more high in over-all dimensions, with beds 15 or 18 feet or even more between uprights and 7 or 8 or more feet deep. The operating mechanisms provided are of such character that they will provide the very large forces required for carrying out the necessary operations, and nevertheless will maintain the relative movement of the parts of the press and the cooperating dies, within such accuracy that thin metal sheets such as are used in automobile bodies, and which are usually about $1/25$ of an inch thick or perhaps slightly thicker, may be formed or drawn to desired intricate shapes, with several sequential forming operations in the same or in different directions, and yet avoiding tearing the metal or causing wrinkling such as will form an impractically large percentage of parts having objectionable high lights when the parts are painted, i. e. with few faulty parts produced in manufacturing operations. These presses therefore must be of such heavy construction that they will perform the required operations, or sequence of operations, in the stamping or drawing of the metal while acting upon the metal sheets under pressures of many hundreds of tons and with the mechanisms nevertheless acting with such precision that only a very small percentage of the formed parts are so marred in formation as to be useless because of tearing or such wrinkling as to require any substantial amount of hand finishing, thus to avoid rejects.

In addition such presses may be so constructed as to be usable with suitable dies and heavy pressures so as to form or draw heavier metal

2

parts, such as the side channel members for an automobile chassis. Such channel or angle bent parts are formed from metal sheets which are much thicker than the sheets for the body and fenders etc., as referred to above, and would therefore require either heavier overall pressures or heavier pressures in a more limited forming die area—i. e. heavier pressures per unit area. That is, in forming the channel members it may be desirable to have a press so constructed that the bed may be 30 feet or more between its supports or up to similar dimensions for die length or between uprights, and narrower than referred to above—e. g., 4 to 6 feet.

15 In all such presses the parts themselves are necessarily very heavy, and must be so in order to withstand the heavy pressures to which they are subjected in operation and also to support the extremely heavy dies and the weight of the parts themselves. A press such as first referred to above, such as for forming automobile body panels, fenders, etc., and having a bed 15 to 18 feet between uprights, will be so constructed as to provide the great strength and rigidity of parts 20 which is necessary in operation; but despite building the parts and the completed press to have such great strength and to withstand such heavy pressure loads, it is generally recognized that there will be appreciable sag or deflection of the bed and movable die slide due to the great operating pressures during the forming operation. For varying operations the deflection in some operations may be more or less than in others, and the permissible deflection of the bed, for example, has been long considered to be up 25 to about .001 of an inch per foot distance between supports. For a press bed 15 feet between supports the deflection or sag midway between the bed ends would be up to about .015 of an inch. And as the movable die slide tends to deflect in the opposite direction, as it is forced down to effect the operating pressures on the work between the dies, its deflection is added to that of the bed. In a rail press, for example, with 30 the bed some 30 feet between supports the bed deflection would be up to .030 of an inch and also the upper deflection of the movable slide is added to that.

Obviously the amount of deflection of the parts 35 will vary according to the construction and weight of the bed member, the construction and points of application of working power to the movable slide, the shape and size, etc. of the dies, the character of the pieces to be formed and the 40 distribution of forces as between the bed and

the die slide, and the pressures required for forming the work. While these serious operating difficulties have been recognized as present in such presses and it has been the general practice to so construct them that the maximum permissible deflection in operation could be held within a predetermined narrow range, having regard to the operations to be performed and the nicety and accuracy of formation required in such operations, nevertheless the effectiveness in press operation has heretofore been circumscribed and the quality of output of a given press, performing varying operations, materially affect it, as some deflection occurs under the heavy operating pressures despite the greatest care in construction of the press parts and imparting great strength to those parts, as some varying deflection has been found inherent in the operation of these presses and this has led to so constructing the press parts as to give a limited maximum permissible deflection which could be taken into account in the operating of the press. And in practical operations improved expedients such as the use of shims to compensate for extra large or variable deflections, or where the pressures are abnormally distributed, have been used by press operators in an endeavor to meet the particular conditions confronting them and to effect workable compensations for the particular work being done.

One of the principal objects of the present invention is to provide a mechanically operating stamping or drawing press of the character referred to, which is provided with means whereby sag or deflection may be readily maintained within known and permissible limits and may be automatically compensated for to give more precise and accurate operation, and more certain results in operation.

Another object of the invention is to provide a press with a die carrying member which is pivotally supported so that variations in deflection or deformation as between the two die supporting members may be more readily maintained within practical operating tolerances and compensated for, and deformation of one die carrying member to accommodate itself to deflections or sag in the other may be readily accomplished with improved operating results.

Still another object is to provide a composite die carrying member comprising two parts pivotally interconnected and in which deflection or sag may be readily maintained within a narrow range of operating tolerances and may be readily automatically compensated for with improved operating results.

Another object is to provide such press structure which is compact, requires comparatively low head room, and which may be readily assembled and disassembled and in which a unitary composite die slide and driving mechanism is provided which may be assembled as a unit and placed in the press structure as such.

Other objects and advantages of the invention will be apparent from the description and drawing and the appended claims.

In the drawing, in which like characters of reference designate like parts throughout:

Fig. 1 is a side elevational view, somewhat diagrammatical, showing a press of such construction with parts broken away and shown in section, along the line 1—1 of Fig. 2, for more clearly illustrating details of construction;

Fig. 2 is an end elevational view of the construction shown in Fig. 1;

Fig. 3 is a top plan view of the press;

Fig. 4 is a side elevation, with parts broken away and in section to show details of construction, of a modified form of press having a composite die slide;

Fig. 5 is a side elevational view of another modified form of press construction, having the driving motor and other parts of the driving mechanism located below the bed;

Fig. 6 is an end elevational view of the construction shown in Fig. 5, with certain parts broken away for simpler and clearer disclosure;

Fig. 7 is a plan view, broken away and shown partly in section along the lines 7—7 of Fig. 5 and 1a—1a of Fig. 6; and

Fig. 8 is a bottom view of the front portion of the press illustrated in Figs. 5 to 7 to show details of the driving mechanism.

In the embodiment of the invention illustrated somewhat diagrammatically in Figs. 1—3 of the drawing, the press is shown constructed for forming channel frame members for an automobile chassis, or other long channeled or angled or otherwise bent members out of sheets of metal; and in such construction the distance between uprights is considerably greater than in presses as ordinarily used for forming quarter-panels, fenders and other automobile body parts out of thin sheet steel as above referred to. In the form of construction illustrated the distance between uprights may be thirty or more feet, and the depth of the bed, where comparatively narrow channel members or the like are to be formed, some four to six feet.

The press of this invention has simple and effective means for compensating for tendency towards deflection or sag in the bed, and the bolster plate and die carried thereby, and also such deflection or sag as may occur in the movable die carrying member so that with the press constructed to keep deflection or deformation of the parts within a permissible tolerance range any deflection may be readily compensated for by the simple and highly effective provisions of this invention. The same is true with respect to the embodiment of the invention illustrated in the two point suspension crank press of Fig. 4, and the modification of Figs. 5—8 in which the composite movable slide member is used but with the form of drive and power applying mechanism in which the motor and mechanism for transmitting power to slide operating linkage is located below the bed instead of on the slide itself as in the construction of Figs. 1—3.

As shown in the embodiment illustrated in Figs. 1—3 the press comprises a bed member 29 which is suitably supported upon a concrete floor, or other suitable foundation members. As shown the working floor line is illustrated diagrammatically at 21 and supporting ledges, or series of pillars, by the numeral 22. The floor line, as illustrated, is approximately level with the top of the press bed; and such presses are constructed so that with a fixed bed, in the form of press shown, and a fixed lower die member which is illustrated diagrammatically in simple form and designated 25, the upper surface of this die 25 will be at such level that the operators may readily insert the sheets of material to be formed into the press, a considerable portion of the press thus extending down below the work floor into a suitable pit or other space below the floor.

The bed is preferably a hollow casting, with 75 suitable reinforcing ribs and peripheral flanges;

and may be adapted to receive air cushions, as well understood, and as illustrated in my copending application Serial No. 458,686, filed September 17, 1942. The bolster plate 26 is secured to the bed in any suitable way, as by means of bolts, or bolted wedge members as illustrated in said copending application, and the bolster plate is provided with the usual means for receiving bolts to hold the lower die member in position, and may be provided with the usual holes to receive pins for cooperating with the pressure cushions.

Cooperating with the bed and spaced therefrom a suitable distance, which distance will depend upon the stroke of the movable die slide, is a rectangular framework designated at 30 illustrated diagrammatically as made up of separate members, with the side and end pieces suitably bolted or otherwise rigidly connected together. Interposed between the rectangular ring or frame portion 30 and the bed are four tubular spacing or side members 35, each of which is suitably connected at its lower end to the bed 20 and at its upper end is in engagement with the frame portion 30. A plurality of tie rods or bolts 36 is provided, each of which is threaded at each end. Each of these bolts extends through one of the spacer members 35 and has its lower end extended through a passage in the bed member which is coaxial with the corresponding spacer member 35 and has a nut 37 upon the lower end which can be tightened properly against a lower portion of the bed. Likewise each upper end of each bolt 36 passes through a passage in the crown portion 30 which is in alignment with the passage in a cooperating spacer member 35 and the upper threaded end of each bolt is also provided with a nut 37. By properly adjusting the nuts 37 and 37' the bed and frame member, spaced between members 35, may be held in rigid connected relation to form a bed and upper frame and side uprights of the press structure or framework.

Also provided in each end of the part 30, and midway between the pair of tie rods at each end, is an enlargement carried by the crown portion and designated 40, which has a passageway therein receiving a cylindrical sleeve 41 having a flange 42 at the bottom thereof which abuts against the lower face of enlargement 40. This sleeve 41 likewise has an inturned flange 43 at the upper end which receives a hollow threaded sleeve 45, having an external shoulder 46 which abuts against the inturned flange 43 and is held in position by means of an adjusting ring 50, which is in driving connection with the sleeve 45, and which rests against the upper face of the frame 30 and is held in locked position against this upper face by means of a nut 51 which is connected to the upper end of the sleeve 45. Threadedly mounted within the sleeve 45 is a threaded link member 55, the lower end of which is enlarged as shown at 56 and carries a pivot or wrist pin 57 upon which is pivotally adjusted the crank or eccentric arm 58 of an eccentric strap 59. The eccentric strap is mounted upon the eccentric 65, which in turn is interconnected with a driving gear 66, both the eccentric and its driving gear being rotatable upon a cross shaft 67.

The cross shaft 67 is carried by a slide member 70, there being two of these eccentric and driving gear members 65—66, each supported by a shaft 67, one of these shafts being shown at each end of the slide 70. The construction of

the eccentric, adjustable link mechanism and the other parts for the right-hand end of Fig. 1 are the same as parts described just above for the left-hand end, as viewed in Fig. 1.

The slide member 70 also carries suitable support for a motor 75, which drives a pulley and fly wheel 76, mounted upon a shaft 77 and provided with clutch and control mechanism so that the shaft 77 may be rotated from the power source or motor 75, or disconnected therefrom under suitable controls, the mechanism illustrated and described in my referred to copending application being satisfactory for this purpose and the driving mechanism being therefore shown somewhat diagrammatically in the present application. In this driving mechanism, as in my referred to copending application, the construction is such that by means of a series of gears 68—68' the power is transmitted from the shaft 77 to the eccentric gears 66, and so to the connecting rods 53, by means which includes the same number of gear contacts and which therefore have substantially the same number of points of mechanical friction or lost motion, as a result of which the power is transmitted substantially equally to each of the eccentrics so that the slide which is actuated by them will be caused to follow a substantially true rectilinear path of movement, and with no material or objectionable transverse or side thrusts.

The inner slide 70 is provided with a pivot pin 80, located about midway of its length, which pin extends through the upper side walls of the inner slide 70, and acts as a pivotal support for an outer slide 85, which is the die carrying slide in this instance, the upper die being diagrammatically illustrated and designated at 88.

This outside slide 85, as shown is generally channel shaped in cross section, with its side walls braced by end cross pieces 86, and it may be provided with suitable reinforcing ribs and the like.

It will be clear that as the motor operates, it will act through the diverging gear trains to rotate the gears 66 and the eccentrics 65 carried thereby and this in turn will cause the eccentric strap and connecting rod attached to it to raise and lower the inner slide 70, with the entire driving power exerted at the opposite ends thereof through the shafts 67. This power is transmitted from the inner slide 70 through the pivotal pin 80 to the outside slide 85, this pin 80 being located substantially midway between the ends of the outside die carrying slide 85. As pressure is exerted against the slide 85 this pressure will be exerted at substantially the midpoint. Since the bed, as shown, is supported at its opposite ends, any deflection in the bed would tend to reach its maximum substantially midway of the ends of the bed. And by means of the construction of composite pivoted slide above set forth, the downward pressure exerted upon the die carrying slide 85 during operation will be substantially at the same midpoint and consequently any deflections which occur may be readily compensated for. A composite die carrying member comprising two parts pivotally interconnected may thus greatly reduce the inherent deflection or sag and may also automatically compensate for any such deflection and permit of using less massive parts, with economy in manufacture of the press and in replacement parts and also of securing more accurate and desirable operating results. And very satisfactory operating results are secured by the embodiment of the invention shown

in which the movable die carrying slide has the die carrying member pivotally connected to the other associated slide member midway the ends thereof, and the operating power is applied to said associated member at its opposite ends and from it through the central pivot pin to the die carrying member.

In order to prevent the pivoted slide 85 from uncontrolled or excessive movement about the pivot pin 86, the inner slide 70 is provided with two pins 90, one adjacent each end thereof, and these pins project through openings in the outside slide each having enough clearance to permit the slight movements of the outer slide due to deflections or deformations in operation, but with the clearance so limited, to a small fraction of an inch, as to correspond to the maximum permissible deflection of the cooperating die carrying member but sufficient to permit the slight movement of the limit pins occasioned by deflection of the outer slide on opposite sides of the supporting pivot pin 86. In the construction here shown this clearance for these limit pins satisfactorily would be substantially less than the amount of maximum permissible deflection of the bed. Thus the outer slide cannot move materially away from the horizontal or the desired positioning with respect to the bed and, so it cannot bind in operation or take an undesirable positioning as a result of non-uniform distribution of forces within the die during the stamping or forming operation; but nevertheless it will automatically deflect and adjust itself adequately under operating pressures to compensate itself for the deflections of the cooperating die carrying member and the dies during a work operation. With the operating pressure on the pivoted slide exerted midway of its free ends, and thus at the zone of greatest deflection of the bed and in the direction of the bed deflecting forces, this compensating action is automatically brought about and enforced by the press operation, in each instance.

This embodiment of press, as stated, is particularly adapted for forming sheets of metal into channel members such as are used as side frame members in an automobile, and it is therefore shown as narrow from front to back as compared with the distance between the supporting points for the bed or the distance between uprights. And in such construction, the members 35 at each end are spaced apart a sufficient distance to permit of feeding or sliding a long and comparatively narrow sheet into the press through one end and so feeding them properly onto the lower die, and after the forming operation withdrawing the formed pieces through the corresponding opening between the members 35 at the other end of the press. This makes for considerably greater ease and effectiveness in handling of such sheets and parts formed therefrom. Also it permits of placing the press in line with other presses or machines operating on the sheets or parts formed therefrom, and thus makes for greater over-all manufacturing economy and efficiency. For purposes of comparison, an adequate understanding of the over-all dimensions of the press shown and of the parts thereof may be secured from reference to the statement above that the upper face of the lower die 25 is horizontally so positioned with respect to the work floor 21 that the workman can readily feed the metal sheets into the press. From this it is evident that the gears, eccentrics and the like for transmitting the power are of very massive construction, as

illustrated, for example, in connection with the eccentric gear 66 and the eccentric strap 59 and attached connecting rod 58, as shown in Fig. 2. Because of the thickness of these gears 66, and the eccentrics 65 and the straps 59 associated with them, in a comparatively narrow and long press, as illustrated, the power may be adequately applied along the central zone of the bed and slide, using only two of the eccentric strap and adjustable link mechanisms—a so-called two-point power applying construction. In presses having wider beds, so that the two-point construction might not give sufficiently rigid support for the die slide to withstand any tendencies of the slide to cock and bind as a result of pressure applied away from the points of support shown, a four-point construction may readily be utilized as shown in my copending application referred to.

As shown, all of the operating mechanism is carried by the movable slide and below the upper end of the press mechanism, thus providing a more compact structure, with all the operating mechanism readily accessible and with greatly reduced hazard for workmen since the distance of the operating mechanism from the floor is greatly reduced and furthermore operators working upon this mechanism when it is within the press are protected against falling, against being accidentally knocked off by traveling cranes and the like, by the top framework 30. And such construction also provides a highly satisfactory operating mechanism with lower head room so that the parts of the press may be readily handled by shop cranes.

The upper framework 30 is shown diagrammatically as built up of structural members bolted or otherwise rigidly connected together. For example, the four enlargements 93 through which the tie rods or bolts 36 pass may be separately formed, and provided with means whereby they may be bolted or otherwise properly secured to the two side members or connecting bars 91 and two short end pieces or bars 92, each such bar being constructed to be bolted or fastened at each of the ends to said enlargements, by bolts marked 91'. As shown in Figs. 1 and 3 an end of one of the longer cross bars is shown as bolted to one of the four enlargements 93. By means of this construction, the removal of the bolts 91' will permit of removal of the side and end pieces of the upper framework member 30 and this in turn will permit of removing the entire upper slide with its driving and pressure applying mechanism, as a unit. And this also permits of maintaining such a unit as a spare, so that if a unit in the press becomes inoperative it may be quickly removed and another put in its place without disassembling the whole press and the disabled unit repaired or provided with replacement parts in due course and without holding up the manufacturing operations of the press, or the whole line of presses and machines of which it forms a part. Such a unit may be removed and a new one installed in a few hours, and this makes for great manufacturing advantage and economy, since disabling of one essential press or machine in a line stops the whole line and therefore results in loss of time and of products far in excess of that which would be occasioned by mere stopping of a single press operating alone.

Because of the construction described in which the operating pressures are exerted in tension, with the adjustable links having long bearing extent and being sufficiently massive to prevent

any objectionable deflection under the work pressures during the forming part of the press cycle, the disturbing effect of any transverse forces which may be exerted at the wrist pins 57, due to small angular movement of the eccentric strap connecting rods 58, presents no problem and causes no objectionable results in operation. The construction is such that with the parts properly manufactured, the adjustment of the pressure transmitting linkage at the respective ends of the slides may be such as to give substantially rectilinear motion of the slide. Suitable guide members may be provided upon the outside of the movable slide and upon the uprights 35, as shown in the above noted Patent No. 2,378,062, so that through cooperation these guide members will be effective to take up any transverse forces exerted at the wrist pins during operation. And by having the operating linkage arranged so that these forces will be exerted in opposite directions they may be balanced and thus more readily compensated for.

As shown diagrammatically each adjusting nut 50 is provided on its outer face with inclined teeth adapted to mesh with a worm gear edge 96, gears for the adjusting nuts being carried by an operating shaft 97 driven by driving gears 98 from a suitable adjusting motor 99 mounted on the crown, so that up and down adjustment of the threaded link 55 may be readily accomplished to vary the distance of the movable slide from the bed. These parts are shown diagrammatically as it is not thought necessary to illustrate this construction in detail as it may be substantially the same as the corresponding construction shown in my referred to copending application, with such minor necessary structural modifications as to permit of mounting this nut adjusting mechanism upon the slide.

In the embodiment shown in Fig. 4 the composite pivoted die slide is shown included in a conventional type of stamping press. This press comprises a bed member 100 and a crown member 101, with the uprights 102—102' interposed between them and firmly held together in the usual manner by large tie rods 103. In this construction the upright or side frame member 102' is provided with a supporting bracket 104 carrying the fly wheel and clutch assembly designated generally by the numeral 105, and which is driven, by means of belts or the like, from a motor 106, mounted on an extending platform attached to the top of the crown. The uprights 102—102' have provisions for receiving and supporting the crank shaft 110, which has a driven gear wheel 111 which is in meshing engagement with the gear (hidden behind the gear wheel 111) by means of which power is transmitted from the driving motor through the fly wheel and clutch assembly to the gear wheel 111 and so to the crank shaft 110. In the construction shown this crank shaft is provided with two operating cranks 112, and the crown is provided with depending portions 113 in which the crank shaft is rotatably supported.

Connected to each crank 112 is a connecting rod 115, the lower end of which is connected by means of a suitable wrist pin to an inner reciprocable slide member 120. Surrounding this inner slide is a hollow outer slide 121, which is adapted to receive the upper die 132 and has guide faces 122 engaging with the guides 123 to give properly directed reciprocating motion to the composite slide as the crank is revolved during operation.

The inner slide member 120 is connected to the outer slide member 121 by means of pivot pins 130, each of which, as shown, may have its ends held in aligned openings in the sides of the inner and outer members 120—121, and the outer member is thus supported midway of its length by a pivotal connection between the two members of the composite slide. Likewise, as shown, the inner member 120 carries two limit pins 131, each of which extends through openings in the walls of the outer member 121, which openings have small clearance for the pins. These openings also are sufficiently large to permit ready deflection of the outer pivoted slide, and the die parts carried thereby, to compensate for deflection or sag of the bed and bolster plate and the lower die 133 and the upper movable slide and the parts carried thereby, in a manner heretofore described, and the clearance around the limit pins is a small fraction of an inch—only sufficient to permit deformation of the pivoted slide member 121, to meet deflection within the tolerances encountered in operation of the press, but this clearance is so small that any substantial pivoting of the slide as a whole, with consequent binding with other parts, or interference with the proper operation is prevented.

The connecting rods 115 are pivotally connected to the inner slide member 120 adjacent its outer ends, and this connection may be by means of wrist pins mounted in an adjustable member, which may be properly actuated by motor drive to provide for lengthening or shortening the connecting rods and thus varying the distance of the composite slide from the bed 100, as shown for example in patent, A. A. Byerlein, No. 1,817,885, August 4, 1931, and diagrammatically illustrated and designated by the numeral 135.

In the modified construction of press, of Figs. 5, 6, 7 and 8, the press is shown as comprising a bed member 200 which is provided with supporting standards or feet 201, which are likewise diagrammatically shown as resting upon supporting masonry or other suitable support members, illustrated and designated 202.

The floor line is indicated at 205, the press as illustrated therefore having substantially half of its extent above the floor line 205 and the other half below. The press is so located with respect to the floor line that the lower die, when supported in the press, will be at such height that the workman may readily feed the sheets of metal, to be formed, into the press when standing upon the work floor 205. As illustrated the floor line is approximately level with the top of the bed member 200, and a pit is provided below the floor into which the lower half of the press extends. This need not be an actual pit, as diagrammatically illustrated for purposes of simplicity, but it may be merely a suitable space provided in a lower part of the building beneath the press workroom floor, in which event suitable supporting columns, or supporting cross beams, would be provided as support for the feet portions 201.

The bed member 200 as shown is a hollow casting, having suitable internal and external strengthening flanges or ribs 230. It is adapted to receive a bolster plate designated by the numeral 231, this plate extending over the open bed and being provided with suitable means, such as usual bolt receivers, whereby the lower die member may be fastened thereto. This lower die is illustrated in very simple diagrammatic form in

Fig. 5 and designated by the numeral 232, the upper male die being correspondingly illustrated and designated by the numeral 233. The bolster plate is connected to the bed by means of suitable bolts or bolt-members as shown for example in my copending application referred to; and if desired air cushions may be utilized in the bed in the usual way also as shown for example in my said copending application.

The upper die 233 is suitably connected, as by means of bolts, not shown, to an upper movable die support member 240. This die support member 240 is illustrated as part of a composite or compound die slide, the part 240 being supported by means of a pivot pin 245, which is shown as located approximately midway of the length of the member 240, and which has its opposite ends mounted in an outer die slide member 250. This outer die slide member is hollow, being provided with braces or strengthening ribs 251, and with peripheral strengthening flanges 251'. As shown, more particularly in Fig. 7, the outer die slide member 250 is provided throughout its major extent between the sides, or upright members at the sides, of the press with parallel walls spaced apart sufficiently to receive between them the inner die carrying member 240.

At each end corner the outer slide member has hollow enlargements 255 formed thereon, each enlargement having a passage therethrough to receive the power transmitting linkage, and the top of each of these enlargements is substantially horizontal as shown to receive a plate member 260, which is bolted thereto, and travels with this outer slide member 250 during operation of the press. Bolted or otherwise suitably attached to each member 260 is a hollow housing member 261, within which is mounted the upper end of a link 265 which in turn is firmly held in vertical position, as shown, by bearings or supporting collars or sleeves 266, which collar or sleeve 266 has a passage therethrough to receive the link in adjustable support.

The length of each link or rod 265 which extends up into this holding sleeve extension 261 is made sufficient to provide the bearing surface or support which will hold it in its predetermined axial position, and the size of the several links are such that no substantial or objectionable bending or deflection will occur during operation of the press mechanism. The extension 261 has a passage 270 at its upper end which is in alignment with the passage in the member 266 and is covered over by an inverted cup shaped member 271, adequate passage length for axial adjustment of each link to give proper variation in stroke of the upper die slide being thus permitted without adversely affecting the rigidity of the links in operation. The lower end of each link 265 is bifurcated to provide two extensions 275, which carry a supporting pin 276, which has pivotally mounted thereon the upper enlarged end 277 of a connecting rod 278, the lower end of which carries an eccentric strap 279, which receives a driving eccentric 280.

The eccentric 280 receives driving power during operation of the press from power applying mechanism to be hereinafter described, and the construction is such that as the several eccentrics 280 rotate the connecting rods 278 are correspondingly moved so that the pins 276 are moved a distance determined by the throw of the eccentric and this in turn transmits reciprocating motion to the links 265. And since these links are supported from the members 260 which are

rigidly connected, as by means of strong bolts or the like, to the outer slide member 250, the driving power is transmitted equally to the opposite ends of this member 250. As shown, the power in turn is transmitted from the outer slide member 250 by means of the pivot pin 245 approximately midway of the inner die carrying pivoted slide member 240 so that up and down motion is imparted to the member 240 and the die member carried thereby. Thus, also, the members 240 and 250 are pivotally connected, with the operating power exerted against the outside ends of the member 250 and transmitted therefrom at substantially its mid-point through the pivot

pin 245 to the inner slide member 240, and the operating power for the upper die carrying slide is exerted through this pivot pin 245 and is made effective half-way the length of the inner member 240.

The bed, along with the bolster plate and lower die member carried thereby, is supported at its outer ends and its effective length for deflection is the distance between its supports. Since the upper die carrying member 240 has the power applied substantially at its midpoint, the maximum downward pressure exerted upon this upper slide 240 and the die carried thereby, during operation of the press, will be substantially at the zone or line of greatest possible deflection of the bed and lower die. By means of such interconnection and interrelationship of parts, the pivoted upper slide member 240 will accommodate itself to the lower die, and the maximum pressure being exerted at the zone of greatest deflection will more readily compensate for any deflection or sagging within the permissible range, as is true in the other modifications herein.

In order to maintain the upper pivoted slide member 240 in substantially the positioning desired and to prevent undue rocking about the pivot 245 with possible serious consequence in a large press exerting so much pressure upon the dies and the parts carrying them, the pivoted slide 240 and the outer slide 250 are shown as interconnected, adjacent their outer ends, by means of the two limit pins 285 and 285'. These limit pins are firmly mounted in one of the slide members, and pass through aligned openings in the other slide member which have a slight clearance sufficient to permit the deformation or deflection of the pivoted member 240 during operation, but still so limited to a small fraction of an inch as to prevent objectionable and undesirable pivoting of the slide 240 about its supporting pivot pin 245. As described above, the pins 285 and 285' may be suitably held in aligned openings in the outer slide 250 and pass through aligned openings in the inner slide 240 where the necessary clearance is provided, or they may be mounted in the inner slide member with the desired small amount of clearance provided in aligned openings in the outer slide member. In the press construction as here shown, the clearance for the limit pins 285 and 285' will be a small fraction of an inch as above set out.

Bolted to the bed member, at each corner thereof, is an upright or standard 290, each such standard being in cross section substantially as shown in Fig. 7, the bolts holding its lower end to the bed being indicated at 290'. Also bolted to the upper end of each corresponding pair of standards 290 is a cross bar frame member 291, which is firmly bolted at each end to its cooperating standard 290 by bolts 292. Also, cross

supporting bars 293, corresponding to parts 291 are provided which are bolted in between pairs of the standards 290, at the upper ends thereof. By means of this construction a framework is provided which is firmly supported from the bed member, and which has the upper ends of the standards 290 firmly held together by means of the cross bars 291 and 293 so as thus to hold the upper ends of these standards interconnected and to provide the firm framework referred to.

The pairs of members 290 are adapted to receive between them and to guide the ends of the outer slide 250; suitable pillow blocks or guide members 295 (Fig. 7) being provided for this purpose, which cooperate with corresponding parts of each of the four corners of the outer slide member 250. Also the plate members 260 each has attached thereto a rod 300, which is the piston rod for a counterbalance cylinder 301, the piston 302 being slideably mounted in each such cylinder to provide a counterbalance device for the composite slide 240—250.

Positioned between the lower face of each end of each side member 291 and the top of the bed, is a hollow tubular member 305, each of which provides ample space for receiving a connecting rod 278, and which serves to enclose its rod and protect it from dirt and injury. These members 305 may have bolt flanges 306 at the top by which each may be bolted in place against the bottom of the cross bars 291, the lower ends setting in depressions 307 formed in the top of the bed.

In the construction described, as in the construction described in my referred to copending application, the forces are exerted in tension during the work performing part of the cycle of the press. In other words, with the parts as shown in the drawing, the upper composite die carrying slide, which is shown as a movable one, is in its uppermost position, the eccentrics 280 being so positioned that the connecting rod 278 and the links 265 are in substantial alignment. The work having been introduced with the press parts in this position, operation of the driving means to rotate the eccentrics 280, will cause downward movement of the upper ends of the connecting rods and the pins 276 and as these parts are carefully manufactured and adjusted the force exerted downwardly upon the movable composite slide 240—250, will be substantially uniformly exerted at each corner and this movable die carrying member and its die will tend to receive straight linear motion. And through completion of the forming or stamping operation this rectilinear movement is maintained, subject only to such slight tendency toward transverse forces exerted at the pins 276 as results from the comparatively slight rocking motion of the connecting rods about such pins due to the rotation of the eccentrics. But as is evident, the connecting rods 278 are quite long compared to the travel of the bed and the length of the links 265, and the axes of the power transmitting pins 276 are positioned considerably above the lower face of the die carrying slide, and consequently such comparatively slight rocking motion of the connecting rods will have no material or objectionable effect. But the downward pull effective upon the upper composite die carrying slide will be substantially a straight rectilinear one. Furthermore by having the eccentrics arranged to travel in opposite directions in moving the eccentric straps, adverse tendency of transverse forces effective at the pivot pin 276 can be generally compensated for. And in any event the links 70

265 are of considerable size, as is obvious, being at times as much as 10 or 12 inches in diameter, or whatever diameter may be required to give sufficient rigidity to withstand the operating forces. Thus the standards 290, with the interconnecting cross pieces 291 and 292 provide a framework however which is of adequate strength to absorb any transverse force exerted at these pivot pins 276, whether upon up or down motion of the movable slide.

The transmission of power to the eccentrics 280 is accomplished by means of suitable power driven gear trains so arranged that the same number of power transmitting members are positioned between the driving motor 315 and each eccentric, so that mechanical losses and play and other forces will be equally divided to give substantially uniform driving force effective at each of the four corners. As illustrated the motor 315 is provided with a driving pulley 316 which carries a plurality of drive belts 317, which engage a larger pulley 318 mounted upon a shaft 319, which is supported at each side of the press, from a depending bracket 320, to provide a cross shaft 25 which is properly supported at each end.

The pulley 318 is connected to a flywheel 325; and the pulley and flywheel assembly are adapted to rotate continuously upon the shaft 319, during operation of the drive motor, and suitable clutch and control mechanism therefor is provided so that when suitably actuated the clutch will engage the flywheel, to cause rotation of the shaft 319 at the same time releasing a brake, substantially in the manner described in my above referred to copending application. The shaft 319 carries a gear 330 at each end, each of which gears meshes with a pair of gears 331 and 332—the gear 331, as shown in Fig. 5, being adapted to transmit power to the right hand corner eccentric and the gear 332 to transmit power to the left hand corner eccentric. The gear 331 meshes with a cooperating gear 333, carried upon a shaft 334, which shaft carries a pulley 335 thereon, that pulley being connected by means of suitable belts to another pulley 336 mounted upon a shaft 337 which shaft carries a gear 338 at each end thereof, each of these gears being adapted to mesh with one of the large eccentric drive gears 339, each mounted upon a shaft 340. Each shaft 340 carries an eccentric 280, and through the members of the power transmitting train described, power is transmitted from the motor 315 to the eccentric 280. Power is likewise transmitted equally through gears 345, 346, pulley 347, pulley 348, gear 349 to the large eccentric gear 339 at the left corner of Fig. 5 so that there is an equal transmission of power with equal mechanical friction and lost motion to the eccentric gear 339. There are two eccentrics for the other or backside of the press which are likewise driven in the same manner but not illustrated, as adequately illustrated and described above, and there are also similar gears, pulleys, etc. for the backside of the press the same as described above. Thus a four point drive, that is a drive for each corner of the slide is secured, with substantially uniform transmission of power by the diverging gear trains to give the rectilinear motion of the slide as described.

While the forms of apparatus herein described constitute preferred embodiments of the invention, it is to be understood that the invention is not limited to these precise forms of apparatus, and that changes may be made therein without

departing from the scope of the invention which is defined in the appended claims.

What is claimed is:

1. In a stamping and drawing press of the character described, a bed having provisions for receiving a die, a movable composite slide member for supporting a cooperating die, said composite member comprising a hollow part and a second part movably positioned therein, means for connecting said outer hollow part to the press power transmitting mechanism whereby operating movement is imparted to said part, means for pivotally interconnecting said parts to transmit the operating power from said outer part to the inner part, said inner part having provisions for receiving the die, said pivotal connection having the axis thereof substantially transverse of the direction of reciprocation of said composite member and being located to transmit power to said inner pivoted part at the zone of maximum deflection of said bed during the forming operation to automatically cause compensation for deflection of said bed under the work pressures in the forming operation.

2. In a stamping and drawing press of the character described, a bed having provisions for receiving a die and supported adjacent its ends with an intermediate zone thereof subject to maximum deflection under operating pressures, a movable composite slide member for receiving a cooperating die, said composite member comprising a hollow part and a second part movably positioned therein, means for connecting one of said parts to the press power transmitting mechanism whereby operating movement is imparted to said part, means for pivotally interconnecting said parts to transmit the operating pressure from said one part to the other, said other part having provisions for receiving the cooperating die, and means for guiding said die receiving part during operating movement thereof to maintain the same in proper alignment with said bed, said pivotal connection between said parts having the axis thereof substantially transverse of the direction of reciprocation of said composite member and being located to transmit power to said other pivoted part at said zone of maximum deflection of said bed during the forming operation to automatically cause compensation in deflection of said bed under the work pressures in the forming operation.

3. In a stamping and drawing press of the character described, a bed member supported adjacent its ends with an intermediate zone thereof subject to maximum deflection under operating pressures and having provisions for carrying a die, a movable composite slide member, said composite member comprising a hollow part and a second part movably positioned therein, means for connecting one of said parts to the press power transmitting mechanism whereby operating movement is imparted to said part, means for pivotally interconnecting said parts to transmit the operating power from said one part to the other part, means carried by the other part for receiving a die member for cooperation with the die carried by said bed to effect a forming operation, said pivotal connection between said pivoted parts having the axis thereof substantially transverse of the direction of reciprocation of said composite member and being located substantially midway between the ends of said other pivoted part to transmit power to said other pivoted part at said zone of maximum deflection of said bed and in the direction of deflection during

the forming operation to automatically cause compensation for deflection of said bed under the work pressure in the forming operation.

4. In a stamping and drawing press of the character described, a bed member supported adjacent its ends with an intermediate zone thereof subject to maximum deflection under working pressures, frame means supported above said bed, adjustable links carried by said frame means, a composite slide member within said frame, said composite member comprising a hollow part and a second part movably positioned therein, power transmitting mechanism carried by the composite slide member, connecting rods connecting one of said parts to said links, means operably connecting said connecting rods and said power transmitting mechanism to cause reciprocation of said composite slide member in working operation of the press, means for pivotally interconnecting said parts to transmit the operating pressure from said one part to the other part, said other part having provisions for receiving a die, said pivotal connection between said parts having the axis thereof substantially transverse of the direction of reciprocation of said composite member and being located to transmit power to said other pivoted part at said zone of maximum deflection of said bed during the forming operation to automatically cause compensation in deflection of said bed under the work pressures in the forming operation.

5. In a stamping and drawing press of the character described, a bed member supported adjacent its ends with an intermediate zone thereof subject to maximum deflection under operating pressures, frame means supported above said bed, adjustable links carried by said frame means, a composite slide member within said frame means, said composite member comprising a hollow part and a second part movably positioned therein, power transmitting mechanism carried by the composite slide member, connecting rods connecting one of said parts to said links, means operably connecting said connecting rods and said power transmitting mechanism to cause reciprocation of said composite slide member in working operation of the press, means removable from the frame means whereby said composite slide member and driving mechanism may be removed from or introduced into the press as a unit while maintaining the assembly of the rest of the press parts, means for pivotally interconnecting said parts to transmit the operating pressure from said one part to the other part, said other part having provisions for receiving a die, said pivotal connection between said parts having the axis thereof substantially transverse of the direction of reciprocation of said composite member and being located to transmit power to said other pivoted part at said zone of maximum deflection of said bed during the forming operation to automatically cause compensation in deflection of said bed under the work pressures in the forming operation.

6. In a stamping and drawing press of the character described, a bed member supported adjacent its ends with an intermediate zone thereof subject to maximum deflection under operating pressures, frame means supported above said bed, adjustable links carried by said frame means, a composite slide member within said frame means, said composite member comprising a hollow part and a second part movably positioned therein, power transmitting mechanism carried by the composite slide member, connecting rods connect-

ing one of said parts to said links, means operably connecting said connecting rods and said power transmitting mechanism to cause reciprocation of said composite slide member in working operation of the press, means for pivotally interconnecting said parts to transmit the operating pressure from said one part to the other part, said other part having provisions for receiving a die, said pivotal connection between said parts having the axis thereof substantially transverse of the direction of reciprocation of said composite member and being located to transmit power to said other pivoted part at said zone of maximum deflection of said bed during the forming operations to automatically cause compensation in deflection of said bed under the work pressures in the forming operation, and limit pins permitting said deflection compensation while maintaining said pivoted part against objectionable movement about said pivotal connection.

7. A stamping press of the character described comprising a bed supported adjacent its ends and having provisions for supporting a die, a crown member, spaced uprights between said bed and crown, means for holding the bed and crown and uprights tightly together, a crank shaft supported in the upper part of said press, power means for operating said crank shaft, a movable composite slide, connecting rods supporting said slide from said crank and for causing reciprocation of said slide in said press, said composite slide comprising an inner part operatively connected to said connecting rods and an outer hollow part having guide means, cooperating guide means on said uprights, said outer part of said composite slide having provisions for receiving an upper die, and a pivotal connection between said parts of the composite slide located substantially midway between the ends thereof for transmitting operating pressures from the inner to the outer part during forming operation at the zone of maximum deflection of said bed during the forming operation and in the direction of deflection of the bed to automatically cause compensation for deflection of said bed during said forming operation.

8. A stamping press of the character described comprising a bed supported adjacent its ends and having provisions for supporting a die, a crown member, spaced uprights between said bed and crown, means for holding the bed and crown and uprights tightly together, a crank shaft supported in the upper part of said press, power means for operating said crank shaft, a movable composite slide, connecting rods supporting said slide from said crank and for causing reciprocation of said slide in said press, said composite slide comprising an inner part operatively connected to said connecting rods and an outer hollow part having guide means, cooperating guide means on said uprights, said outer part of said composite slide having provisions for receiving an upper die, a pivotal connection between said parts of the composite slide located substantially midway between the ends thereof for transmitting operating pressures from the inner to the outer part during forming operation at the zone of maximum deflection of said bed during the forming operation and in the direction of deflection of the bed to automatically cause compensation for deflection of said bed during said forming operation, and limit pins permitting said deflection compensation while maintaining said pivoted

part against objectionable movement about said pivotal connection.

9. In a press of the character described, a bed for receiving a die, means for supporting said bed adjacent the ends thereof with the deflection thereof under working pressures reaching a maximum at a zone intermediate said ends, a reciprocable slide comprising a pair of relatively movable slide members arranged one within the other, one of said members being adapted to receive a cooperating die, drive means for effecting reciprocating movement of said slide, pivot means connecting said slide members and having its axis arranged transversely thereof in the plane substantially parallel with said bed ends and passing through said zone of maximum deflection of said bed, and means forming a driving connection from said drive means to the other of said slide members to transmit working pressures to said die carrying slide member in said plane through said pivot means and to compensate for deflection of said bed and the die carried thereby under said working pressures by complementary deflection of said die carrying slide member.

10. In a press of the character described, a bed supported adjacent its ends and adapted to receive a die with the deflection thereof reaching a maximum intermediate said ends, a reciprocable slide including a pair of separate slide members, one of said members being adapted to receive a cooperating die, drive means for effecting reciprocating movement of said slide, means operably connecting the other of said slide members with said drive means, pivot means connecting said slide members to form the driving connection from said other slide member to said die carrying slide member, said pivot means having its axis located transversely of said slide member in the plane of said maximum deflection to compensate for said deflection of said bed and the die carried thereby under working pressures by complementary deflection of said die carrying slide member and said cooperating die, and means adjacent the periphery of said die carrying slide member for guiding the same in proper alignment with said bed during the working stroke of said slide.

11. In a press of the character described, a bed supported adjacent its ends with the intermediate portion thereof subject to deflection under working pressures and adapted to receive a die, a composite slide member for carrying a cooperating die, drive means for effecting reciprocating movement of said slide member, said slide member including a part having a driving connection with said drive means and a second part adapted to receive said cooperating die, and pivot means connecting said two parts and having its axis extending transversely of said slide in a plane substantially parallel with and intermediate said bed ends to transmit working pressures to said die carrying part and bed during work operations along said pivotal axis and to compensate for deflection of said bed and the die carried thereby under said working pressures by complementary deflection of said die carrying slide part and the die carried thereby.

12. In a press of the character described, a bed supported adjacent its ends with the intermediate portion thereof subject to deflection under working pressures and adapted to receive a die, a composite slide member for carrying a cooperating die, drive means for effecting re-

reciprocating movement of said slide member, said slide member comprising two relatively movable parts, one of said parts being adapted to receive said cooperating die, means adjacent opposite ends of the other of said parts forming driving connections with said drive means, and pivot means forming a driving connection from said other part to said die carrying part, said pivot means extending transversely of said slide member and substantially parallel with said bed ends and midway between said driving connection means to compensate for deflection of said bed and the die carried thereby under working pressures by complementary deflection of said die carrying slide part and said cooperating die.

13. In a press of the character described, a bed supported adjacent its ends with the intermediate portion thereof subject to deflection under working pressures and adapted to receive a die, a composite slide member for carrying a cooperating die, drive means for effecting reciprocating movement of said slide member, said slide member including a part having a driving connection with said drive means and a second part adapted to receive said cooperating die, pivot means connecting said two parts and having its axis extending transversely of said slide in a plane substantially parallel with and intermediate said bed ends to transmit working pressures to said die carrying part and bed during work operations along said pivotal axis and to compensate for deflection of said bed and the die carried thereby under said working pressures by complementary deflection of said die carrying slide part and said cooperating die, and limit pins carried by said composite slide member for permitting said deflection compensation while maintaining said die carrying part against objectionable movement about said pivotal connection.

14. In a press of the character described, a bed member supported adjacent its ends with the intermediate portion thereof subject to deflection under working pressures and adapted to receive a die, frame means supported from said bed, a composite slide supported by said frame means, power transmitting mechanism comprising a motor and power transmitting means carried by said bed, link means having one end adjustably connected to said composite slide, means for transmitting power from said mechanism to the other end of said link means to effect rectilinear reciprocating motion of said composite slide, said composite slide comprising an outer part and an inner part movably positioned therein and having means for receiving a die, means for pivotally connecting said parts substantially midway of the ends of said inner part to transmit forming pressure therebetween, said link means being operably connected to said outer part of said composite slide and transmitting power thereto for work movement, said pivotal connection being located to transmit forming pressure between the dies in the zone of maximum deflection of said bed and in the direction of said deflection to effect automatic compensation for relative deflection in the bed and composite slide member and the dies carried thereby.

15. In a press of the character described, a bed member supported adjacent its ends with the intermediate portion thereof subject to deflection under working pressures and adapted to receive a die, frame means supported from said bed, a composite slide supported by said frame means, power transmitting mechanism comprising a motor and power transmitting means carried by

said bed, link means having one end adjustably connected to said composite slide, means for transmitting power from said mechanism to the other end of said link means to effect rectilinear reciprocating motion of said composite slide, said composite slide comprising an outer part and an inner part movably positioned therein and having means for receiving a die, means for pivotally connecting said parts substantially midway of the ends of said inner part to transmit forming pressure therebetween, said link means being operably connected to said outer part of said composite slide and transmitting power thereto for work movement, said pivotal connection being located to transmit forming pressure between the dies in the zone of maximum deflection of said bed and in the direction of said deflection to effect automatic compensation for relative deflection in the bed and composite slide member and the dies carried thereby, and limit pins permitting said deflection compensation while maintaining said pivoted inner part against objectionable movement about said pivotal connection.

16. In a stamping and drawing press of the character described, a movable composite slide for supporting a die member, stationary means for supporting a cooperating die member, means mounting said stationary die supporting means adjacent opposite ends thereof with the intermediate portion thereof subject to deflection under operating pressures applied thereto by said slide, power transmitting means for causing reciprocation of said slide to effect a working operation of said die members under forming pressure in a working cycle of said press, said composite slide comprising a first part operatively connected to said power transmitting means and a second part adapted to carry said die member, pivotal means located substantially centrally of said second part for pivotally connecting said second part to said first part and constructed to transmit driving power to said second part for effecting forming pressure of said die members, said pivot means having the axis thereof substantially transverse of the direction of reciprocation of said slide, said pivotal connection being substantially opposed to said unsupported intermediate portion of said stationary die supporting means to effect automatic compensation for variations in deflection of said stationary die supporting means and the die carried thereby by complementary deflection of said die carrying slide part.

17. In a stamping and drawing press of the character described, a composite die carrying slide, a die carrying member, a drive for effecting cooperating relative movement of said slide and said member to effect forming pressure of the dies supported thereby, means supporting said die carrying member with a predetermined zone thereof subject to maximum deflection under said forming pressure, said composite slide including a first part operatively connected to said drive and a second part adapted to carry the die, a pivotal connection between said parts for transmitting working pressure from said first part to said die carrying part, and means for guiding said die carrying part to maintain the same in proper alignment with said die supporting member, said pivotal connection being located substantially opposite said zone of maximum deflection of said die carrying member to effect automatic compensation for deflections occurring in said die carrying member during a forming operation,

21

18. In a stamping and drawing press of the character described, a composite die carrying slide, a die carrying member, a drive for effecting cooperative relative movement of said slide and member to effect forming pressure of the dies carried thereby, means supporting said die carrying member with a predetermined zone thereof subject to maximum deflection under said forming pressure, said composite slide including two parts with one of said parts movably positioned inside the other, means operatively connecting one of said parts to said drive, the other said part being adapted to carry the die, and means forming a pivotal connection between said parts for transmitting working pressure to said die carrying part from the other of said parts and with the axis of said connection substantially transverse of the direction of relative movement of said slide and member, said pivotal connection being located substantially opposite said zone of maximum deflection of said die carrying member to compensate for deflections occurring therein during said forming operations by effecting automatic complementary deflection of said die carrying slide part.

19. In a press of the character described, a bed adapted to receive a die, means for supporting said bed adjacent its ends with an intermediate portion of said bed subject to deflection under working pressures, a reciprocable slide comprising a pair of slide members, one of said members being adapted to carry a cooperating die, pivot means forming a connection between said slide members with the axis thereof extending transversely of said slide in opposed relation to said intermediate portion of said bed, drive means

22

for effecting reciprocating movement of said slide, means forming a driving connection from said drive means to said other slide member to apply working pressure to said die carrying slide member through said pivot means in the plane passing through said pivot axis and intermediate said bed ends to compensate for deflection of said bed and the die carried thereby under said working pressures by complementary deflection of said die carrying slide member and said cooperating die, and means cooperating with said slide to maintain said die carrying slide member in proper alignment with said bed throughout the working stroke of said slide.
